CLAIM

The ornamental design for a timer, as shown and described.

DESCRIPTION

FIG. 1 is a top view of a timer showing my new design;

FIG. 2 is a front view thereof;

FIG. 3 is a right side elevational view thereof;

FIG. 4 is a bottom view thereof;

FIG. 5 is a rear view thereof; and,

FIG. 6 is a left side view thereof.

The rectangular display in the middle of the front of the timer in FIG. 2 is flat and flush with the adjacent portions of the timer case.
